UNITED STATES PATENT OFFICE.

KARL KISSENDORFER, OF OBERNDORF-ON-THE-NECKAR, GERMANY, ASSIGNOR TO
WAFFENFABRIK MAUSER, A. G., OF OBERNDORF-ON-THE-NECKAR, GERMANY.

SCREW CLAMP.

Application filed May 8, 1922. Serial No. 559,394.

To all whom it may concern:

Be it known that I, KARL KISSENDORFER, a citizen of the German Republic, residing at No. 22 Rottweilerstrasse, in the city of 5 Oberndorf-on-the-Neckar, Germany, have invented certain new and useful Improvements in Screw Clamps (for which I have filed the following applications: in Germany, February 11, 1922; Austria, March 10, 1922; 10 Czechoslovakia, March 10, 1922; Yugoslavia, March 4, 1922), of which the following is a specification.

This invention relates to a screw-clamp or cramp of the kind comprising a rigid bow 15 or U-shaped body the one shank of which affords the stationary jaw for the work to be clamped, while the other shank has its end formed into a threaded opening or eye for the reception of a manually operable 20 threaded spindle, the inner end of which affords the other jaw of the holdfast or cramp.

Adjustable tools of the described type also 25 comprise a releasing means for disengaging the threaded spindle from the female thread of its guiding shank in order to allow an initial or preliminary rough adjustment of the jaw in accordance with the size of the work to be clamped, and to then engage the 30 female thread with the spindle for the subsequent manual operation of clamping the work fast between the jaws with the aid of the spindle as is usually done in ordinary holdfasts.

Said releasing means preferably consists 35 of a segmental portion of the eye pivotally connected to the latter and having on its semicylindrical inner face a female thread conforming to the spindle thread, while all 40 the other portions of the said eye are not threaded, so that when the aforesaid segmental portion is turned out about its pivot the spindle will be free to axially move in 45 the eye, and when said portion is turned in or closed, the spindle will be gripped by the female thread thereof and cannot move except on the path or track of the thread.

Now, it has been found, that, when the 50 thread of a screw-clamp of the adjustable type, as above described, has worn out by frequent use, the axial pressure of the spindle will be diverted laterally, acting to disengage the pivotal threaded portion of the eye, so that, if this occurs, the spindle will 55 be free to move in the unthreaded portion

of the eye and there will be no clamping effect.

The object of this invention is to remedy this defect by providing a means for locking the pivotal threaded portion of the eye, when closed, with the aid of the pressure force, so that when the spindle is under clamping strain there will be no liability for the threaded eye portion to disengage from the spindle.

The specific construction of the tool is fully illustrated in the drawings, in which—

Figure 1 is a side elevation of the screw-clamp with the improved thread guiding and locking arrangement in closed position 70 and with the work clamped tight between the two jaws of the tool,

Figure 2 is a similar view with the work loose in the gap between the jaws,

Figure 3 is a section on the line A—B 75 of Figure 1,

Figure 4 is a section on the line of A—B of Figure 2,

Figure 5 is a section on the line C—D 80 of Figure 1 and Figure 6 is a section on the line of C—D of Figure 2.

Like letters designate corresponding parts in all of the figures of the drawing.

Referring to the drawing the letter *a* 85 designates the segmental portion or member of the eye having the female thread and pivotally connected with or hinged to the upper shank of the bow *c* by means of a bolt *b*. At the inner end of the segmental portion or member *a* a lug *d* is provided, 90 said lug having a curved or sloping face or incline at its outer end to conform to the correspondingly shaped recess *f* in the contacting face or end of the unthreaded major portion *i* of the eye. The member *a* commonly assumes a position with relation to the eye portion *i* as shown in Figures 1 and 5.

The pivot or bolt *b* consists in the shown embodiment of the invention of an ordinary screw-bolt with its shank firmly screwed 100 into the ear *k* of the member *a* and with its head loosely fitting in a bore *l* of the upper shank of the bow *c*. A coiled spring *g* is provided on the bolt in the bore *l* so as to abut with its ends against the head 105 of the bolt and the bottom face of the bore respectively and thus keep the member *a* constantly in contact with the unthreaded portion *i* of the eye, as shown in Figure 1, 110 as long as the member *a* retains its closed

position. If, however, the spindle *e*, instead of being under strain, as in Figure 1, is loose, as in Figure 2, and consequently also the threaded member *a* is not under strain, the latter can be turned out or opened by means of the tail or handle *h*, whereby its female thread is disengaged from the thread of the spindle *e* and the parts are caused to assume the position shown in Figure 2.

In consequence of the oscillation of the member *a* about its pivot *b* the lug *d* slides outwards over the inclined face of the recess *f*, from the position illustrated in Figure 3 to that shown in Figure 6, and at the same time the contacting faces of the unthreaded portion *i* of the eye and of the member *a* separate against the action of the spring *g*, from the position shown in Figure 1 to that illustrated in Figure 2. The spindle *e* then is thoroughly free within the eye, as shown in Figures 4 and 6, and can be speedily adjusted to the size of the work *n*, as shown in Figure 2. This done the handle *h* is released so that by the action of the spring *g*, the member *a* is drawn inwards and upwards with the lug *d* sliding back into the recess *f*, until the female thread of the member *a* again is in engagement with the thread of the spindle *e*. In turning the latter down by means of its handle *m* to engage with the work *n* and by forcing the jaw *o* into firm contact with the work *n* as illustrated in Figure 1, the pressure of the thread of the spindle on the thread of the member *a* ensures a firm locking engagement of the lug *d* in the recess *f*, as shown in Figure 5, so that the member *a* cannot disengage from the spindle thread, even in case the threads are considerably worn.

From the foregoing description, it will be seen that simple and efficient means are herein provided for accomplishing the objects of the invention, but while the elements shown and described are well adapted to serve the purposes for which they are intended, it is to be understood, that the invention is not limited to the precise construction set forth, but includes within its purview such changes which may be made within the scope of the appended claims.

Having now particularly described and disclosed the nature of the invention and in what manner the same is to be performed, what is claimed is:—

1. An adjustable screw-clamp, comprising a bow having a shank at each end, one of said shanks having an opening therein, and

also a recess; a spindle associated with the opening of said shank; a thread member having a bolt for pivotally securing the member to the last-named shank, and provided with screw threads adapted to coact with said spindle; a lug on said member adapted to coact with said recess; and a spring on said bolt for forcing said member against said spindle.

2. An adjustable screw-clamp, comprising a bow having a shank at each end, one of said shanks being provided with an opening and also a recess having an inclined surface; a spindle associated with the opening of said shank; a thread member having a bolt for pivotally securing the member to the last-named shank, and provided with screw threads adapted to coact with said spindle; a lug on said member adapted to coact with the inclined surface of said recess; and a spring on said bolt for forcing said member against said spindle.

3. An adjustable screw-clamp, comprising a bow having a shank at each end, one of said shanks having an opening therein, and also a recess having an inclined edge; a spindle associated with the opening of said shank; a thread member having a bolt for pivotally securing the member to the last-named shank, and provided with screw threads adapted to coact with said spindle; a lug on said member adapted to coact with said recess; and a spring on said bolt for forcing said member against said spindle, said thread member being adapted to move parallel with said spindle by means of said bolt when the spindle is rotated.

4. An adjustable screw-clamp, comprising a bow having a shank at each end, one of said shanks having an opening therein, and also a recess having an inclined edge; a spindle associated with the opening of said shank; a thread member having a bolt for pivotally securing the member to the last-named shank, and provided with screw threads adapted to coact with said spindle; a lug on said member adapted to coact with said recess; and a spring on said bolt for forcing said member against said spindle, said thread member being adapted to move parallel with said spindle by means of said bolt sliding in its socket in said shank and to rotate against the action of said spring when said lug is out of engagement with said recess.

In testimony whereof I affixed my signature.

KARL KISSENDORFER. [L.S.]
